UNITED STATES PATENT OFFICE.

JOHN E. CLEMENS, OF PAMPA, WASHINGTON.

CURRYCOMB.

1,050,103.

Specification of Letters Patent. Patented Jan. 14, 1913.

Application filed February 28, 1911. Serial No. 611,316.

To all whom it may concern:

Be it known that I, JOHN E. CLEMENS, a citizen of the United States, residing at Pampa, in the county of Whitman and State of Washington, have invented certain new and useful Improvements in Currycombs, of which the following is a specification, reference being had to the accompanying drawings.

10 My invention relates to new and useful improvements in devices used in the care of live stock, and more particularly to the class of devices known as curry combs, and my object is to provide a curry comb with 15 means thereon for cleaning the same.

A further object is to provide a slotted cleaning plate adapted to coöperate with the comb sections of the device to clean the same, and a further object is to provide 20 spring means to retain the same out of operative position.

A still further object is to provide improved means for disposing said plate in effective position.

25 With these and other objects in view, my invention consists in the novel features of construction, combination and arrangement of parts, as will be hereinafter referred to and more particularly pointed out in the 30 specification and claim.

In the accompanying drawings, forming a part of this application, Figure 1 is a top plan view of the device; Fig. 2 is an end elevation thereof; Figs. 3 and 4 are sectional views, as seen on lines 3—3 and 4—4, Fig. 1; Fig. 5 is a detail perspective of a lever for operating the cleaning plate; and Fig. 6 is a detail perspective of the cleaning plate removed.

40 In carrying out my invention, I shall refer to the drawings, in which similar reference characters designate corresponding parts throughout the several views, and in which 1 indicates a frame, to the under face 45 of which are secured a plurality of comb sections 2, which are channel or U-shaped in cross-section, and have their lower edges toothed, as at 3. These channel or U-shaped comb sections are secured to the frame by 50 means of the studs or the like 4, and as the sides of the frame are bent downwardly in alinement with the comb sections, and have their lower edges also toothed, a perfect curry comb will be formed.

55 The usual, or any preferred form of bracing member 5, is provided, on the upper

face of said frame 1, having one end thereof bifurcated to form outwardly bent arms 6 and 7, and the other end thereof being bent upwardly, as at 8, from the frame, to form 60 the supporting stem for the handle 9. When this bracing member 5 is properly secured to the frame, and the handle mounted at one end thereof, the usual form of curry comb will have been formed, and it is more 65 particularly to a cleaning mechanism for the comb sections in such a curry comb, that my invention relates. To this end I provide a plate 10, which fits between the ends 11 and 12 of the frame 1, and extends transversely the full width thereof, and said plate is provided with a plurality of transversely extending slots 13, which register with each of the comb sections, which are, in turn, adapted to extend therethrough. In order 70 to prevent the plate leaving the frame, pins 14 are provided, which are mounted in said plate and extend through openings in the top of said frame, said pins being provided with heads 15, which are larger than the 80 openings through which the pins extend. A transversely extending U-shaped member or arched bar 16 is secured at its ends to the plate 10, the arms of said bar passing freely through openings in the frame. Leaf 85 springs 17 are secured at one end only by rivets or similar fastening devices to the forward corners of the frame, preferably at the outer ends of the diverging arms 6 and 7 of the bracing member 5, said springs extending rearwardly and inwardly toward 90 each other and having their ends slipped underneath, but not fixedly connected to the cross bar of the member 16, whereby the springs will distribute their tension on the 95 plate 10 so as to prevent it from binding in its movements and at the same time, as will be noted, the springs may be very easily assembled as their ends are only slipped underneath the cross bar of the member 16. 100

It is to be noted that the forward ends of the springs 17 are connected to the forward corners of the frame, each by a single rivet, and that the rear relatively free ends of the springs are curved upwardly, after passing 105 underneath the cross bar of the member 16, whereby the springs will be prevented from being accidentally swung around on the rivets as pivots and thus disengaged from the member 16, although if it is desired to free the springs from the arched member 16 to permit the cleaning plate to drop down, this 110

may be easily done by slightly depressing the inner or rear ends of the springs and then turning the springs forwardly toward each other, the length of the cross bar of the 5 arched member also assisting in this operation.

- In order to provide means for imparting a downward movement to the plate 10, whereby the comb sections may be cleaned, 10 10 a trigger or the like 18 is provided, which is disposed immediately under the handle 9, which trigger is formed integral with the base of a pair of arms 19, and forms therewith a substantial Y. These arms 19 straddle the upwardly bent portion 8 of the bracing member 5, and are pivotally mounted about midway of their length on the ends of the shaft 20, which shaft is supported at a point higher than the head of the U- 15 20 shaped member 16, by means of the angular supporting members 21. These angular supporting members are secured to the outer face of the frame on each side of the bracing member 5, and said arms 19 are so positioned as to normally rest upon the head of the U-shaped member 16, whereby when it is desired to clean the sections of the comb, pressure may be placed upon the trigger 12, so as to draw the same toward the 25 30 handle 9, which movement will force the cleaning plate to its lowered or effective position.

The pins 14 are of a length about equal to the depth of the comb sections, so that 35 when pressure has been placed on the trigger, so as to position the plate in its lowered position, the heads 15 of said pins will limit the movement of the plate to the lower edges of the comb sections. This movement, 40 however, is just sufficient to cause the hair and other matter, which may be collected on the teeth of the comb, to be removed therefrom.

The comb may be used in a manner similar to the ordinary comb, until the operator finds that the teeth of the comb have collected too much dirt and filth. At this point it is customary for the operator to use the usual brush, but my cleaning device will 45 50 eliminate the necessity of such a brush, and instead the operator may merely press upon

the trigger below the handle of the comb. This movement, as stated, will dispose the plate in its lowered position to force the filth from the sections of the comb and upon 55 releasing the trigger, said plate will be elevated, through the medium of the springs, to its normal position.

From the foregoing, it will be seen that I have provided an improved means for 60 cleaning the sections of a curry comb, comprising a slotted plate adapted to be lowered into engagement with the teeth of the comb sections, and it will still further be seen that I have provided spring means for 65 normally positioning said plate in its elevated or ineffective position. It will still further be seen that I have provided an improved means for forcing said plate to its lowered position. Furthermore, it will be 70 75 seen that this cleaning means is of such simple construction as to be inexpensively manufactured, and is such as to be easily applied to any curry comb now in use.

What I claim is:

A self-clearing curry comb, comprising a frame, comb bars connected thereto, a cleaning plate formed with slots for stripping said bars, the frame being formed with openings extending therethrough, a transversely extending arched bar connected at its ends to said cleaning plate with its arms freely passing through the openings in the frame, leaf springs connected at their forward ends, each by a single rivet, to the 85 frame at the forward corners thereof, the springs extending rearwardly and inwardly toward each other and having their rear ends extending freely underneath the arched bar at the side arms thereof with their extremities curved upwardly, a handle connected to the frame, and means carried by the frame for engagement with the arched bar to depress the cleaning plate against the 90 95 tension of the springs.

In testimony whereof I hereunto affix my signature in the presence of two witnesses.

JOHN E. CLEMENS.
